(57) **CLAIM**

The ornamental design for a neck mount with electronic device holder as shown and described.

DESCRIPTION

FIG. 1 is a front, right and top perspective view of a neck mount with electronic device holder showing our new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan thereof; and,

FIG. 8 is a bottom plan view; and,

FIG. 9 is an enlarged detailed view of area 9 in FIG. 4. The dash-dot-dash broken lines encompassing the enlarged views are for annotative purposes only and form no part of the claimed design.
